UNITED STATES PATENT OFFICE.

WILBRAND H. ALDENDORF, OF DORMONT, PENNSYLVANIA.

SAFETY-RAZOR.

1,288,463.

Specification of Letters Patent. Patented Dec. 24, 1918.

Application filed July 31, 1918. Serial No. 247,620.

To all whom it may concern:

Be it known that I, WILBRAND H. ALDENDORF, resident of Dormont, in the county of Allegheny and State of Pennsylvania, have 5 invented a new and useful Improvement in Safety-Razors, of which the following is a specification.

This invention relates to safety razors of the type in which the blade is at right angles 10 to the handle.

The objects of the invention are to provide a safety razor of this type which is composed of a few parts of simple construction and is, therefore, cheap to manufacture and 15 easy to keep clean, one which is readily reversible, without taking the same apart, one in which the inactive edge of the blade is shielded so that the user cannot accidentally cut himself, and one which possesses other 20 advantages hereinafter set forth.

In the drawings, Figure 1 is an elevation of the razor looking at the guard plate in end view; Fig. 2 is a similar view showing the head in transverse section; Fig. 3 is a 25 view showing the head of the razor in plan; Fig. 4 is an inverted plan view of the blade and shield and illustrating the manner in which the blade is held by the shield; Fig. 5 is an inverted plan view of the guard plate, 30 blade and shield, showing the manner of securing the blade and shield to the guard; and Fig. 6 is a section on the line 6—6, Fig. 3.

The razor illustrated comprises a handle 35 1, a guard plate 2, a blade 3, and a blade shield or clamping member 4. All of these parts are preferably made of metal or other material which can be sterilized and rendered perfectly sanitary.

40 The handle 1 is a plain solid bar or rod of metal, without cavities or bores, and is provided with the reduced threaded end portion 5 by means of which it is detachably connected to the guard plate 2. This guard plate is of approximately concave or convex 45 form in cross section, or otherwise formed so that its two side portions, that is, the portions at opposite sides of its longitudinal center, are disposed at an angle to each 50 other, as shown in Figs. 1 and 2, and both edges are provided with series of projecting guard teeth 6, as is usual with guards for safety razors. This guard plate is provided centrally with a threaded opening 7 for receiving the threaded end 5 of the handle. The blade 3 is of the double edged variety,

and is disposed on the outer or concave side of the guard plate, and when in use has its active cutting edge partly overlying the guard teeth on that side of the guard. The blade 60 is overlaid by the shield 4, which is of such width that it permits the active edge of the blade to project beyond one of its edges while the opposite or inactive edge of the blade is completely covered so that the user 65 is not liable to cut himself with this edge.

The shield is provided at its ends with downturned guide lugs 8 for the blade and between said guide lugs with turned-under hook-shaped lugs 9, which engage over the 70 ends of and underneath the guard plate, as shown in Fig. 5 and serve to secure the shield to the guard plate. The blade is held in adjusted position by means of the threaded end 5 of the handle, which, when it is 75 screwed fully inwardly, engages the blade rearwardly of its longitudinal center, and thus tilts or cant the blade and shield, brings the forward or active edge of the blade into operative relation to the guard 80 teeth, and clamps the blade and shield firmly in position.

The ends of the guard plate, at its longitudinal center, are provided with notches 10 of sufficient depth to permit the hook 85 lugs 9 to pass therethrough in order to engage on the under surface of said plate, and at both sides of said central notches are shoulders 11 against which the hook lugs 9 abut and which serve as stops to limit the 90 movement of the blade and shield toward the active side of the guard plate, the blade itself being held in proper relation to the shield by means of notches or recesses 12 in its ends, which engage the downturned hook 95 lugs 9. These recesses 12 permit the use of a blade of substantially the same length as the shield to be inserted between the lugs 9, and are of greater width than said lugs to allow sufficient movement of the blade relative to the shield to expose one edge when the blade and shield are adjusted from one side of the guard to the other, when it is desired to use the other cutting edge.

100 The parts are assembled by first inserting a blade 3 in the shield, with its notches 12 engaging the hook lugs 9, and then passing said lugs through the notches 10 in the guard plate, and then moving the shield and blade toward one side or the other so as to 105 bring the ends of the lugs 9 underneath the guard plate, and finally screwing the handle 110

1 fully inwardly, thus tilting the shield and blade around the lugs 9 as a fulcrum and clamping the active edge of the blade in proper operative position with reference to 5 the guard teeth on that side of the guard. The blade can be readily reversed, without taking the razor apart, by partially unscrewing the handle 1, and then swinging the shield over to the other side. Inasmuch as 10 the blade is interlocked with the shield, it moves with it, and when the shield reaches its opposite position, the blade automatically adjusts itself (by reason of the notches 12 being wider than the lugs 9), to expose its 15 opposite edge in operative relation to the guard teeth on that side of the guard, after which the handle is screwed fully inwardly to clamp the shield and blade in this newly adjusted position.

20 The razor described is of very simple construction, comprising only three parts in addition to the blade. All of these parts are of very simple form and can therefore be cheaply fabricated. They are entirely free from recesses, bores and the like, so that they can be readily cleaned by wiping, and, therefore, maintained in a sanitary condition. Both edges of the blade can be utilized and the adjustment from 25 one edge to the other can be made very quickly and easily. The blade can be readily removed for cleaning or replacing with a new blade. The construction permits the use of thick blades, which give better edges 30 and may be re-sharpened to better advantage than very thin blades, and the construction is such that most all standard blades can be used. At the same time the inactive edge of the blade is covered by the 35 shield so that accidental cutting by the back edge of the blade is avoided.

Various changes can obviously be made in the shape and details of construction of the parts, and particularly as the specific 45 way of connecting the shield to the guard plate without departing from the invention as defined in the claims hereinafter following.

I claim:

50 1. In a safety razor, the combination of a guard plate provided with guard teeth on each of its side edges and with a centrally located handle receiving opening, a blade shield detachably connected to the 55 guard plate and arranged to receive a double edged blade between itself and the guard plate, said shield being movable to equivalent positions at opposite sides of the longitudinal center of said guard plate and 60 in either position to cover the inactive edge of the blade, and a handle having its end arranged to engage in and to extend through the opening in the guard plate and engage the blade in either of its two positions rear- 65 ward of its longitudinal center and serving

to tilt its front edge into operative relation to the guard teeth and to clamp the blade and shield in position.

2. In a safety razor, the combination of a guard plate provided with guard teeth 70 on each of its side edges and with a centrally located threaded hole, a shield detachably connected to the guard plate and arranged to receive a double edged blade between itself and the guard plate, said 75 shield being movable to equivalent positions at opposite sides of the longitudinal center of the said guard plate and in either position cover the inactive edge of the blade, and a handle provided with a threaded end 80 extending into and through the threaded hole in the guard plate and engaging the blade in either of its two positions rearward of its longitudinal center and serving to tilt its forward edge into operative relation to the guard teeth and to clamp the 85 blade and shield in position.

3. In a safety razor, the combination of a guard plate provided with guard teeth 90 on each of its side edges and with a centrally located handle receiving opening, the side portions of said plate being disposed at an angle to each other, a blade shield having its ends detachably interengaging with the ends of the guard plate and arranged to rock with reference to said guard to equivalent positions at opposite sides of the longitudinal center of said guard and being arranged to receive a double edged blade between itself and said guard and in 95 either position to cover the inactive edge of said blade, and a handle having its end engaging in and extending through the opening in the guard and engaging the blade in either of its two positions rearward of its longitudinal center and serving to tilt its forward edge into operative relation 100 to the guard teeth and to clamp said blade in position.

4. In a safety razor, the combination of a guard plate provided with guard teeth on each of its side edges and with a centrally located handle receiving opening, the portions of said guard plate on opposite sides of its longitudinal center being disposed at an angle to each other, a blade shield having its end detachably interlocking with the ends of the guard plate and arranged to rock about said connections to equivalent 110 positions at opposite sides of the longitudinal center of the guard, a double edged blade disposed between said shield and the guard plate, stops for limiting the movement of the guard plate in both directions, said 115 blade having a limited movement transversely of the shield, and a handle having its end engaging in and extending through the opening in the guard plate and engaging the blade in either of its positions rearwardly of its longitudinal center. 120 125 130

5. In a safety razor, the combination of a guard plate provided with guard teeth on each of its side edges and with a centrally located handle receiving opening and having the portions at opposite sides of its longitudinal center disposed at an angle to each other, a blade shield disposed on the convex side of the guard, said shield and guard having interlocking detachable hook 10 connections at their ends arranged to permit the shield to rock to either side of the longitudinal center of the guard, stops for limiting the movement of the shield in both directions, a double edged blade disposed between the shield and guard and 15 having interengaging connection with the shield permitting limited transverse movement of the blade relative to the shield, and a handle having its end engaging in and extending through the opening in the guard 20 and engaging the blade in either of its positions rearwardly of its longitudinal center.

In testimony whereof, I have hereunto set my hand.

WILBRAND H. ALDENDORF.
